HAIR STYLING TOOL

Merlyn O. Larson, Spencer, Iowa, assignor to Nylrem
Enterprises Inc., a corporation of Ohio

Filed Dec. 15, 1966, Ser. No. 5,051

Term of patent 14 years

(Cl. D86—8)

I claim:

The ornamental design for a hair styling tool, substantially as shown.
